United States Patent Office

Des. 196,816
Patented Nov. 5, 1963

196,816

DISPENSER FOR OIL OR THE LIKE

Harvey Brody, Los Angeles, Calif., assignor to Norvey,
Inc., Los Angeles, Calif., a corporation of California

Filed Feb. 11, 1963, Ser. No. 73,501

Term of patent 14 years

(Cl. D58—17)

FIG. 1 is an isometric view of a dispenser for oil or the like in closed position embodying my new design;

FIG. 2 is a top plan view of the same;

FIG. 3 is a side elevational view of the same;

FIG. 4 is a fragmentary front elevational view of the same;

FIG. 5 is a fragmentary front elevational view of the same on a reduced scale in open position.

I claim:

The ornamental design for a dispenser for oil or the like, substantially as shown.
